UNITED STATES PATENT OFFICE

WILLIAM SCHEIBEL, OF NEW YORK, N. Y., ASSIGNOR TO BULOVA WATCH COMPANY, INC., OF NEW YORK, N. Y., A CORPORATION OF NEW YORK

RADIO APPARATUS

Application filed March 2, 1931. Serial No. 519,292.

The invention relates to radio receiving apparatus and to combination radio clocks.

One of the objects of the invention is to provide a simple and inexpensive plan to facilitate the setting of the radio dial to frequently used stations.

Another object is to incorporate in the same encased unit an electric clock, a radio receiving set and an electrical connection between the clock and the receiving set whereby the receiving set is started automatically at the time determined by the alarm arrangement of the clock.

In the accompanying drawings forming part hereof:

Fig. 1 is a front elevation of a radio-clock unit embodying the invention;

Fig. 2 is a fragmentary elevation on a larger scale showing the dial for the radio receiving set;

Fig. 3 is a vertical section on the line 3—3 of Fig. 1;

Fig. 4 is a section similar to a portion of Fig. 3, showing a part of a station marker in a different position;

Fig. 5 is a view partly in section and partly in side elevation of one form of station marker by means of which the rotatable dial can be turned and locked;

Fig. 6 is a face view of the same;

Fig. 7 is a view partly in plan view and partly in section of the same form of marker;

Fig. 8 is a side elevation of another form of station marker, which can also be used as a handle;

Fig. 9 is a front elevation of this form of marker;

Fig. 10 is a front elevation of a modified dial member with two station markers of a different type applied to it;

Fig. 11 is a section taken on the line 11—11 of Fig. 10, showing also portions of the slotted wall of the case;

Fig. 12 is a perspective view of one of these markers, with the tablet partly broken away;

Fig. 13 is a section taken on the line 13—13 of Fig. 11; and

Fig. 14 is a similar section illustrating a slight modification.

50 The numeral 2 designates a radio receiv-

ing set, and the numeral 3 a synchronous motor electric clock. Both of these are housed in the same case 4, in such manner that the face of the clock is visible and the controls for the radio set are accessible at the front 55 of the case. A single electrical cable 5 supplies current to both the clock and the radio set. Inside the case there is an electrical connection 6 for conducting current to the radio set, and this connection is controlled by the 60 alarm arrangement of the clock, this alarm arrangement being sufficiently represented by the alarm setting indicator 7. At the time for which this indicator is set the alarm arrangement of the clock completes the circuit 65 to the radio set, and reception will then begin, provided, of course, that the switch and volume control knob 8 has been left in the on position. Customary electrical connections 9, 10 for connecting the radio set with the 70 antenna and with a ground are indicated. The loud speaker 11 is disposed in a suitable manner.

The rotatable dial member of the radio set consists preferably of a sector-shaped 75 plate 12 disposed behind and parallel with the front wall of the case. This dial member is preferably provided with the customary turning knob 13, which projects outside the case and is connected to the dial member 80 at the region where it is rotatably supported. The outer zone 14 of the dial member is marked with the usual graduations and figures, as shown, and the whole of this zone is always visible through an arcuate opening 15 in the front wall of the case, the angular extent of said opening being twice as great as the angular extent of said graduated zone.

The graduated zone of the dial member is 90 further provided with a series of engaging formations, which may be in the nature of small round openings 16 through the plate. The positions of the centers of these openings correspond with the positions of the several 95 graduation marks. To accommodate a complete series of openings in a dial plate of small size the openings may be staggered.

These openings are adapted to receive the stems of station markers, two forms of which 100

are illustrated. The markers 17 are in the form of small buttons or knobs having the stems 18 projecting from their backs. The faces of such buttons carry station designations 19, which may be applied directly to the buttons. It is advantageous, however, to use tablets 20 of paper, celluloid or other material, imprinted with the designations, and to provide the faces of the buttons with flanges 21 forming pockets into which the tablets can be slipped.

The stems are formed to enter any of the holes 16 with a tight drive fit, or other form of frictional or tensional engagement which holds the buttons firmly in place. The buttons can, however, be removed and shifted to other openings, or part or all of the buttons can be removed, and other buttons marked for different stations can be applied at proper positions on the dial. Interchangeability of the markers in respect to a continuous, or substantially continuous, series of possible positions on the dial is of importance to both the manufacturer and the user, since different localities have different prominent broadcasting stations represented by different positions on the dial.

The front panel of the case may have a registering formation at the index position at the center of one edge of the slotted opening 15, this formation being preferably a notch 22, and the station markers may be provided with elements to engage this formation. As one means of accomplishing this I have shown the buttons as being constructed with slidable face portions 23 connected with the back portions 24 by dovetails 25, so that when a button is brought opposite the registering formation its face portion can be slipped into the notch.

The markers are also adapted to serve as knobs or handles for moving the dial quickly and easily to any of the stations whose designations they bear. The markers may be made long enough to project through the slot so that they can be grasped, or the projections which they form may be low, to be pushed by the tip of the finger.

The form of marker designated 17^a illustrated in Figs. 8 and 9 is an angular or bent piece, comprising a stem 18^a and a head 30 of any suitable shape carrying the station designation 19 either directly applied or put on by some equivalent of the tablet described in connection with the other form.

In the form of the invention illustrated in Figs. 10-12, the rotatable dial member 12^b is formed with a slot or opening 40, the upper edge 31 of which is curved concentrically with the top edge 32. One or both of these edges are serrated, or otherwise formed with a series of fine teeth or indentations coextensive with the graduated zone 14^b of the dial members. In this way the dial member is adapted to receive station markers which

may be clipped, or clamped or frictionally engaged with the dial member at the graduated or indicating zone. Such markers may be constructed in various ways.

Sheet metal devices 17^b have been illustrated, the metal being bent to form a front portion 33 which extends across the graduated zone, hook portions 34 to engage over and under the edges 32 and 31, teeth 35 or their equivalent to engage the serrations of these edges, and handle extensions 36. These handle extensions are useful for turning the dial member, and by pressing them toward each other the jaw portions 34 can be spread sufficiently to enable the markers to be applied and removed, or to be changed from one position to another. The lower handle projection may have a notch or mark 37 to facilitate alinement with an index mark 38 on the wall of the case 4. A removable tablet 20^b bearing the station designation may be applied to the front part 14^b in a suitable manner. As shown, the tablet is confined between the handle extensions and is retained by lugs 39.

In Figs. 11 and 13 teeth 35 are shown struck from the sheet metal, whereas in Fig. 14 a riveted tooth 35^b is illustrated.

The edges 31 and 32 need not be serrated if it should not be desired to use the markers as handles for shifting the dial member, and even when they are to be used in this manner the engagement of the markers with the dial member can be firm enough for the purpose.

Numerous other forms and modifications of the markers and of the dial member and of the manner in which the markers are applied to the dial member, may be employed without departing from the scope of the invention.

I claim:

1. In a radio dial, the combination of a rotatable dial member provided with a series of closely related openings, and a plurality of station markers having stems insertible in any of said openings.

2. In a radio dial, the combination of a rotatable dial member, a plurality of station markers adapted to serve as handles for turning said dial member, said markers having attaching elements and said dial member having formations adapted to be firmly engaged by said elements at any of a substantially continuous series of positions along the dial, and a panel having an opening through which all markers are always accessible.

3. In a radio dial, the combination of a rotatable dial member, a plurality of station markers applied to said dial member, and a slotted panel in front of the dial having a registering index formation, said markers projecting through the panel slot and having elements adapted to engage with said formation.

4. In a radio dial, the combination of a ro-

tatable dial member, a plurality of station markers applied to said dial member, and a stationary part having a registering index formation, said markers having shiftable portions adapted to be brought into engagement with said formation.

5. In a radio dial, the combination of a rotatable dial member provided with a series of openings, and a plurality of devices having 10 stems insertible in any of said openings, said devices bearing station designations and being adapted to serve as handles for turning the dial member.

6. In a radio dial, the combination of a rotatable dial member having an indicating zone and slotted to present two edges coextensive with said zone, and a plurality of station markers adapted to embrace and to be engaged with said edges at any positions 20 with reference to said zone.

7. In a radio dial, the combination of a rotatable dial member having an indicating zone and a serrated edge coextensive with said zone, and a plurality of station markers each 25 having a tooth adapted to engage with said edge at any positions with reference to said zone.

8. In a radio dial, the combination of a rotatable dial member having an indicating 30 zone formed with outer and inner edges, and a plurality of shiftable station markers constructed to engage said edges and transversely embrace said zone.

WILLIAM SCHEIBEL.
